W. E. SPAETHE

PNEUMATIC ACTION FOR AUTOMATIC MUSICAL INSTRUMENTS

Filed May 22, 1924

Inventor:

Wilhelm Ernst Spaethe
by *D. J. Dinken*
Attorney.

UNITED STATES PATENT OFFICE.

WILHELM ERNST SPAETHE, OF GERA-REUSS, GERMANY.

PNEUMATIC ACTION FOR AUTOMATIC MUSICAL INSTRUMENTS.

Application filed May 22, 1924. Serial No. 715,117.

My invention relates to automatic musical instruments and more especially to the tune sheets and trackers used in connection with such instruments.

5 As a rule such tune sheet is provided with circular note perforations or with slits extending in parallel to its longitudinal axis. In consequence of this arrangement such tune sheets must be made very long, sometimes more than 100 feet.

It is an object of my invention to reduce this inconvenient length and it will appear from the following description that in reducing the length of the sheet I am also 10 enabled to reduce its width for a given number of rows of perforations or to arrange a greater number of juxtaposed rows of perforations on a tune sheet of given width as was hitherto possible.

20 It is an object of my invention to reduce the size of tune sheets.

It will first be necessary to define what is meant by the "length" and "width" of a perforation, as in my tune sheet the dimension 25 that would usually be termed the "width" is the "length" and vice versa.

The "length" of a slit is therefore that dimension which extends in parallel to the edges of the sheet, and the "width" of a slit 30 is that dimension which extends transversely to said edges.

In a tune sheet having the usual circular perforations or slits made up from a plurality of such perforations combined into a 35 single slit, obviously the length of a perforation is equal to its width and the length of a slit is a multiple of such length or width.

In the usual tune sheets, therefore, the 40 length of a slit is at least equal to its width or it is a multiple of its width.

In my tune sheet on the other hand, the length of a slit is only a fraction of its width.

45 Suppose a circular perforation of the usual type to have the diameter d , and suppose the length of the web between two adjacent perforations to be 1. Then the length of a tune sheet between the ends of 50 two successive perforations will be $2d+1$. Obviously a slit of rectangular shape will have the same effect as a circular perforation if it is of the same area. The width of such a rectangular slit will be greater than 55 the diameter of the corresponding circular

perforation but its length will only be a fraction, say one-third, of its diameter, and so instead of $2d+1$, the length of the sheet as defined above will only be $0.6d+1$.

It has already been proposed to form rectangular slits in a tune sheet the length of which is a fraction of their width and in those tune sheets such slits were combined with slits the length of which exceeds their width, and so the length of the tune sheet 60 could not be reduced. Nor is it an object of such arrangement to reduce the length of the sheet but its object is to provide a tune sheet for instruments having more than a single 65 key board.

70 My novel tune sheet and the described arrangement of its slits, besides reducing the length of the sheet as described, involves two further advantages:

The first advantage is that owing to the 75 greater width of the slits as compared with a circular perforation, lateral deflection of the slits of the sheet with regard to the slits of the tracker is not so detrimental in my tune sheet as in tune sheets having circular 80 perforations or slits the width of which is equal to the diameter of said perforations. The diameter of a perforation is small, about $\frac{1}{16}$ in. as a rule, and if the sheet is deflected for substantially 85 that amount, the note will not be sounded. In my tune sheet, on the other hand, a deflection to this amount will not interfere at all because the area of the tracker slit which 90 the deviated slit in the tune sheet exposes, is still large enough for sounding the note and larger deviations will hardly ever occur.

The second advantage is that my novel tune sheet may be adapted for selectively controlling tracker openings in a single row. In 95 this case, the tracker is provided with, say, three slits, one of which is at right angles to the direction in which the tune sheet is moving, while the other two slits are arranged at either side of this slit and oppositely inclined to said direction at an angle of, say, 45 degrees. Corresponding slits are made in the tune sheet. It will be understood that only those slits in the tune sheet 100 and the tracker are able to cooperate properly which are at the same angle to said direction and that, if an inclined slit meets the right-angle slit of the tracker, the area exposed will be so small that a note will not 105 be sounded.

With this selective arrangement it is possible to combine as many rows of slots into a single row, as there are various inclinations of slits and so the width of the sheet is much reduced. Its length will be increased for the difference between the length of a right-angle slit and the width of an inclined slit projected on the edge of the tune sheet.

As shown in the drawings the circular perforations hitherto provided in tune sheets are replaced by narrow substantially rectangular slits, each slit corresponding to one of the old circular perforations, but having greater width and inferior longitudinal extension. In contradistinction to the slits extending in the longitudinal direction of the old tube sheets, such slits being as a rule formed of a number of consecutive circular perforations merging into one another, the slits according to the present invention extend at an angle to the longitudinal axis of the tune sheet and preferably at right angles thereto. For certain purposes, however, some of the slits may also be disposed at an acute angle to the longitudinal axis of the tune sheets. In the drawings 1, 1 are transversely disposed slits while 2 and 3 are slits disposed at angles of about 45° to the longitudinal axis. The tracker 7 is provided with rows of transversely extending slits 4 and obliquely disposed slits 5 and 6.

Obviously a tune sheet having rectangular slits disposed at an angle to its longitudinal axis, no matter whether it is brought into cooperation with an ordinary tracker or with a tracker provided with slits according to the present invention, offers great advantages as compared with the ordinary tune sheets. A rectangular slit of the kind illustrated in the drawing while presenting the same or a greater sectional area for the passage of air than the circular note perforations is far inferior in length in the longitudinal direction of the tune sheet. It is therefore possible to arrange a greater number of these slits per inch of the length of the tune sheet than with circular perforations and the total length of the tune sheet can therefore be reduced materially or a greater number of perforations can be arranged on tune sheets of given length without the quantity of air sucked or pressed through the sheet being hereby reduced.

With circular perforations a tune sheet on being displaced sideways will not allow air to pass through or the passage of air will at least be greatly reduced.

In order to provide for the case where the displacement of the tune sheet should exceed the usual limits I prefer making the slits in the tune sheet somewhat wider than the perforations or slits in the tracker.

By alternately arranging transverse slits 1, 1 and obliquely disposed slits 2 or 3 in a single row such combined row will replace

two or three juxtaposed rows of ordinary circular perforations. For while the slits 1, 1 will only cooperate with the slits 4 in the tracker the slits 2 will cooperate only with slits 6 and slits 3 with slits 5 in the tracker. In consequence thereof the combination of transversely and obliquely disposed slits allows reducing also the width of the tune sheet.

Obviously a slit 2 or 3 in passing across a slit 4 in the tracker will lay open only too small a cross-sectional area for the passage of air so that no actuation of the mechanism will be obtained and the same is true of the slits 1 with reference to the slits 5 and 6 in the tracker.

It will be understood that the invention involves a great reduction in the consumption of paper and also of air. For in view of the reduced axial length of the slits the tune sheet must be fed across the tracker at a reduced speed and the pneumatic motor driving the tune sheet therefore requires less air. In consequence thereof the instrument requires less physical exertion for its operation.

The term "narrow" used in the specification and in the claims with reference to the slits is meant to indicate that the width of each slit in the transverse direction of the tune sheet by far exceeds its length in the longitudinal or travelling direction of the sheet.

I wish it to be understood that I do not desire to be limited to the exact details of construction shown and described, for obvious modifications will occur to a person skilled in the art.

I claim:—

1. A note sheet for automatic musical instruments having openings therein arranged at an angle to the longitudinal axis of the sheet, said openings being elongated but of substantially the same operative area as the standard note opening, and adapted to cooperate with correspondingly arranged openings of the tracker bar.

2. A note sheet for musical instruments defining note openings the length of which is smaller and the width of which is greater than the diameter of the standard perforation of substantially the same operative area, said openings being adapted to cooperate with openings of the tracker bar.

3. A note sheet for automatic musical instruments having relatively narrow elongated openings arranged at various angles to the longitudinal axis of the sheet, said openings being operative to selectively determine the note to be played by cooperation with correspondingly arranged openings of the tracker bar.

4. A note sheet for automatic musical instruments having elongated openings some arranged at different angles to others and

adapted to selectively cooperate with corresponding angularly arranged openings of the tracker bar.

5. A note sheet for automatic musical instruments having elongated openings therein some of the openings being arranged transversely and some obliquely to the longitudinal axis of the sheet, said openings being adapted to cooperate with correspondingly arranged openings of the tracker bar.

6. A note sheet for automatic musical instruments having relatively narrow elongated openings therein, certain of said openings being arranged at an acute angle with relation to the longitudinal axis of the sheet and others being arranged at a different angle, the different angular positions thereof determining the playing of different notes in the movement of the sheet over the tracker bar.

7. A note sheet for automatic musical instruments having a series of relatively narrow elongated openings, certain of said openings being arranged at an acute angle and certain other openings being arranged at right angles to the longitudinal axis of the sheet.

8. A note sheet for automatic musical instruments having elongated openings therein arranged at various angles to the longitudinal axis of the note sheet, certain of said openings being superimposed upon openings of a different angularity, said openings being adapted to cooperate with openings in the tracker bar angularly corresponding to the openings in the note sheet.

9. In an automatic musical instrument, the combination with a tracker bar having narrow elongated openings disposed at an angle to the longitudinal axis of the note sheet, and a note sheet having correspond-

ingly arranged and similar openings, said openings being operative only when those correspondingly disposed register.

10. In an automatic musical instrument, 45 the combination of a note sheet having elongated openings arranged at various angles with relation to the longitudinal axis of the note sheet, and a tracker bar having an opening angularly corresponding to the openings 50 in the note sheet.

11. In an automatic musical instrument, the combination with a tracker bar having openings therein arranged at different angles to each other, of a note sheet having correspondingly angularly related openings 55 therein adapted to operate selectively only when corresponding openings of the bar and sheet cooperate.

12. In an automatic musical instrument, 60 the combination with a tracker bar having a plurality of rows of openings transversely thereof, the openings in each row being arranged at different angles with relation to each other, of a note sheet having elongated 65 openings therein arranged at corresponding angles to those of the tracker bar openings for selectively cooperating with the bar openings.

13. In an automatic musical instrument, 70 the combination with a tracker bar having a plurality of rows of elongated openings transversely thereof, the openings in each row being arranged at different angles with relation to each other, of a note sheet having 75 openings therein arranged to move over the openings in the tracker bar but operable to effect sounding of a note only when an opening in the note sheet corresponds to the opening in the tracker bar.

In testimony whereof I affix my signature.
WILHELM ERNST SPAETHE.
